(57) **CLAIM**

The ornamental design for a computer stylus, as shown and described.

DESCRIPTION

FIG. 1 is an isometric front upper view of the new design for a computer stylus;

FIG. 2 is an isometric front lower view of the computer stylus;

FIG. 3 is a top view of the computer stylus;

FIG. 4 is a front and back view of the computer stylus;

FIG. 5 is a bottom view of the computer stylus;

FIG. 6 is a left side view of the computer stylus; and,

FIG. 7 is a right side view of the computer stylus.

The dashed lines are for illustration purposes only, and form no part of the claimed design.
